(57) **CLAIM**

The ornamental design for an electric hot air tool, as shown and described.

DESCRIPTION

FIG. 1 is a top, front perspective view of the electric hot air tool.

FIG. 2 is a front elevational view of the electric hot air tool.

FIG. 3 is a rear elevational view of the electric hot air tool.

FIG. 4 is a left side elevational view of the electric hot air tool.

FIG. 5 is a right side view elevational of the electric hot air tool.

FIG. 6 is a top, plan view of the electric hot air tool; and,
FIG. 7 is a bottom view of the electric hot air tool.

The broken line portion of the figure drawings is included to show unclaimed subject matter, only and forms no part of the claimed design.
